LUBRICATING APPARATUS FOR STEAM-ENGINES, &c.

1,370,953.

Specification of Letters Patent.

Patented Mar. 8, 1921.

Application filed June 26, 1920. Serial No. 391,868.

To all whom it may concern:

Be it known that I, PHILIP G. DARLING, a citizen of the United States of America, and resident of Brookline, in the county of Norfolk and State of Massachusetts, have invented new and useful Improvements in Lubricating Apparatus for Steam-Engines, &c., of which the following is a specification.

This invention relates to force feed lubricators such as are employed for injecting lubricating oil into the steam in the feed pipe of steam engines and while herein illustrated as adapted particularly for use in locomotive practice, is in many of its essential features of general application.

While devices of this character are known to the trade, they are in many cases defective in practical operation by reason of the delicacy of the parts employed or their exposure upon the outside of the casing whereby they are unfitted for the rough usage, constant and heavy vibration and unavoidable shocks necessarily attendant upon their use for the purpose intended.

It is also found in practice that by reason of the common occurrence in the oil employed, of sludge, grit or particles of waste or other fibrous matter, the check valves frequently fail to act, requiring a long and laborious operation to dismantle the device for the purpose of clearing the valves.

It is necessary to the successful operation of devices of this character that the pump reservoir shall always contain oil to a height above the intake of the pump, as otherwise air is forced into the space above the check valve, and by reason of the short pump stroke and the heavy back pressure, this air can not be removed except by disconnecting the discharge pipe, and for this reason it is desirable that the pump intake be as low as practicable and that the pump be required to lift the oil through but a short distance on the suction stroke.

It is also desirable to provide simple drive mechanism for the pump piston or pistons which shall be positive in action during the pressure stroke and in which there shall be no undesirable lost motion between the parts.

Devices commonly employed for the purpose are installed in the locomotive cab in order to be readily accessible for inspection and adjustment, but it would be advanta-

geous to provide for the automatic regulation of the oil feed to the end that the entire device might be located outside the cab, thus saving space therein, while at the same time such automatic regulation would insure uniformity of oil feed, thus economizing oil.

In devices of this character it is essential that the terminal check valve commonly installed in the discharge pipe shall be of simple construction and easily cleaned as well as reliable in operation, many of the valves now employed failing to give satisfactory results.

In the production of a lubricating device for the purpose above described the object in view has been to devise an apparatus in which the above noted defects and deficiencies in the prior art devices are overcome or avoided and which will embody all such desirable features as may conduce to the successful operation and continued and uninterrupted use of such a device.

To the above end and in accordance with this invention the lubricator may be so constructed as to have all its essential operative parts entirely inclosed in a strong and rigid casing having provision for ready attachment to the locomotive frame.

The device may also comprise a self contained pump element comprising the pump cylinder or cylinders with their pistons, the pump intake, check valve or valves and a portion of the oil discharge passages all of which may be arranged for ready removal as a unit from the main casing for cleaning or repairs and without necessitating the drawing off of the oil from the casing.

For actuating the piston or pistons an intermittently rotating shaft may be employed having a cam or equivalent means for actuating the piston on its pressure stroke and spring means for moving the piston on its suction stroke. The intermittent movement of the shaft can conveniently be obtained by the use of a ratchet or equivalent drive actuated from some adjacent reciprocating part such as the main steam valve gear, and preferably such drive will include a locking ratchet to provide against any backward rotation or lost motion in the shaft.

For simplifying the pump mechanism and for insuring its proper operation and feeding of the oil thereto, the cylinder may be

located at a point below the normal level of oil in the casing so that no suction valve is necessary, thus avoiding one common source of trouble in pumps as ordinarily constructed, while at the same time the location of the operative parts below the normal level of the oil insures a constant and thorough lubrication of such parts.

The terminal check valve in the discharge pipe may be of the ball type but to insure proper operation under all conditions this valve may be provided with a spring pressed stem, the inclosing casing for the valve comprising disconnectible parts whereby ready access may be obtained to the valve and its coöperating members for cleaning or repairs, the spring serving to keep the valve seated even under abnormal conditions such as, for example, when a vacuum is formed in the feed pipe when the locomotive is drifting.

As illustrative of a preferred arrangement for obtaining the object and advantages above outlined, reference may be had to the accompanying drawings, in which—

Figure 1 is a fragmentary diagrammatic elevational view of the front portion of a locomotive, illustrating the application of the device of this invention thereto;

Fig. 2 is a transverse vertical sectional view to enlarged scale, on the line *a*—*b*, Fig. 6;

Fig. 3 is an end elevation from the right-hand side of Fig. 2;

Fig. 4 is a plan view of the device shown in Fig. 2 on the line *c*—*d* thereof, parts being broken away;

Fig. 5 is a cross-section on the line *e*—*f* of Fig. 2;

Fig. 6 is a section on the line *g*—*h* of Fig. 2;

Fig. 7 is an elevation to enlarged scale, looking from the right-hand side of Fig. 2, of the roller ratchet device.

Fig. 8 is a view similar to Fig. 7, but looking from the left-hand side of the ratchet device as viewed in Fig. 2;

Fig. 9 is a cross-section through the roller-ratchet device on the line *m*—*n* of Fig. 7;

Fig. 10 is a fragmentary side elevation of the drive shaft showing the cam mounted thereon; and

Fig. 11 is a longitudinal cross-section to enlarged scale through the terminal check valve.

Referring to Fig. 1,—1 is the locomotive cylinder, 2 the valve chest, 3 the piston rod, 4 the cross-head, 5 the valve rod, and 6 the steam feed pipe, all of usual and well-known construction. 7 indicates the lubricating device forming the subject matter of this invention mounted in position for use upon the locomotive frame, and 8 indicates generally a reciprocable connection receiving its movement from the cross head, and by

means of which the moving parts of the lubricating device are actuated.

Referring more particularly to Fig. 2,—10 is a casing of substantially rectangular form, open at its upper end and provided with a series of lugs 11 having openings 12 therein through which suitable bolts or other connections may be passed for attaching the casing to suitable supporting means on the locomotive frame. As the arrangement of the casing and of the attaching lugs 11 is symmetrical, it is possible to mount the lubricating device upon either side of the locomotive with equal facility. At its bottom the casing is provided with a boss 13 having an opening therein normally closed by a plug 14, such opening serving as a convenient means for draining oil from the casing if occasion arises for so doing. 15 is a vertical rib projecting inwardly from the right-hand wall of the casing as viewed in Fig. 2 and having therein a chamber 16 in which may be mounted a gage glass 17, there being an opening at the end of the casing through which the gage glass may be inspected. As seen in Fig. 6, the interior of the gage glass communicates by means of a passage 18 with the interior of the casing 10, whereby fluid contained in said casing is permitted to rise within the gage glass. As the gage glass is relatively short and its lower end is well above the bottom of the casing, accidental breakage of the glass does not occasion the loss of all the oil, a sufficient amount remaining in the lower part of the casing for any reasonable period of use.

The interior wall of the casing opposite the rib 15 is provided with a longitudinal vertical rib 20, this rib being cored out to provide a steam chamber 21, whereby the contents of the casing 10 may be kept at the proper temperature. For admitting steam to the chamber 21 and for draining the condensed steam therefrom, openings 22, 23 and 24 may be provided leading into said chamber from the exterior of the casing, such openings being tapped for pipe connections. It is to be understood that but one of the openings 23, 24 will be in use at one time, the other being closed by a suitable plug, the provision of two openings, however, facilitating the attachment of the drainage pipe regardless of whether the latter is to lead in a horizontal or vertical direction.

Upon its right-hand outer face, as viewed in Fig. 2, the casing 10 is provided with a series of outwardly extending bosses 25, the purpose of which will be hereinafter made evident.

Casing 10, as above stated, serves for the reception of the lubricating medium, and within the casing is also mounted the pump element which, as herein disclosed, comprises a plate 26 having a flange 27 adapted to rest

upon the upper edge of the casing and to be supported thereby. The plate 26, at its right-hand edge as seen in Fig. 2, has a flange 28 of less depth than the flange 27, 5 and engaging beneath said flange 28 is a cover member 29 which extends across the open top of the casing 10 and rests at 30 upon the upper edge thereof at the opposite side, a lug 31 extending downwardly and 10 against the inner wall of the casing 10 to properly position the member 29 relatively to the casing. 31 is a screw passing downwardly through an opening in the cover member 29, and engaging a lug 32 integral 15 with the rib 15. The cover member 29 has an upwardly-extending boss 33 provided with an opening giving access to the interior of the casing 10. A lug 35 extends upwardly from the upper surface of the cover member 29, and pivotally secured to said lug by means of a pin 35^a is a cap 36 which fits down over the boss 33 for closing the opening therein. The hole in the cover member through which pin 35^a passes is 20 somewhat larger than the diameter of the pin whereby the cover is permitted to seat itself securely upon the outer surface of the boss 33. The opening in the boss 33 is of relatively large extent as compared with the 25 casing 10, and has projecting downwardly therefrom a strainer 37 of foraminous material, this strainer extending well down into the casing and forming a large receptacle into which the lubricating medium may be 30 poured. The plate 26 may be secured in position upon the casing by means of a screw 38 passing through an opening therein and engaging a threaded hole in the upper end of the rib 20. Extending downwardly from 35 the plate 26 is a pair of legs 39, 40, these legs and the parts associated therewith being of duplicate construction. In the following description, but one of the legs with the parts supported thereby will be specifically described.

Referring now more particularly to the leg 39, numeral 41 indicates a chamber extending longitudinally thereof, said chamber being closed at its upper end by a plug 42 having a passage 43 therein leading to a connection 44 to which a pipe, as 45 Fig. 1, may be attached, said pipe leading to the terminal check-valve connection 46 (see Fig. 11). At its lower portion the chamber 41 is provided with a pair of ball valves 47, 48 respectively, said valves being mounted one above the other, and acting independently. 49 is a retainer having screw-threaded engagement with the interior of the leg 39, 50 said retainer serving to limit the vertical rise of the ball 47. The lower end of the leg 39 is provided with a foot 50 which is arranged to be seated between the inner wall of the casing 10 and a lug 51 projecting vertically upward from its bottom wall, such

foot, together with the screw 38 serving to retain the pump element in proper operative position in the casing.

Projecting from the right-hand side of the leg 39 near its lower end is a boss 52, said boss being provided with radial flanges 53 and 54 adjacent its opposite extremities, and having a central bore 55 which serves as a pump cylinder. The bore 55 is extended at 56 to a point below the chamber 41, and communicates therewith by means of a passage 57, the upper end of which is normally closed by the aforesaid ball 48. From a point in said pump cylinder 55 intermediate its ends leads a passage 58 which opens 60 into the lower part of the casing 10, such passage serving as the pump intake. 59 is a cylindrical screen or strainer of wire netting or other suitable material surrounding the boss 52 and having its ends seated upon 65 the flanges 53, 54, respectively. This screen 59 thus mounted serves to inclose the entrance to passage 58 and to form thereabout an annular chamber.

Slidable within the pump cylinder is a 90 piston 60 having the piston-rod 61 integral therewith, it being noted that the piston 60 is of uniform diameter throughout that portion which travels within the cylinder. By forming the piston in this manner and by 95 making the cylinder of substantial length, the necessity for packing the piston-rod is avoided.

The piston-rod 61 is guided within guide members 62, 63 extending outwardly from the end of the boss 52, said guide-members being slotted at intermediate points in their lengths. 64 is a key passing through the rod and having its opposite extremities projecting outwardly therefrom and engaging in 100 the slots of the guides 62, 63. The key 64 thus prevents the piston rods from being accidentally displaced from the guides, while at the same time the slots permit the proper movement of the piston-rod within 110 the guides.

The piston-rod at its right-hand extremity is provided with an enlarged head 65 forming a shoulder 66 against which one end of a coil spring 67 may bear, said spring 115 surrounding the piston-rod and the guides and engaging at its opposite extremity the right-hand end of the boss 52.

68 is a yoke member having a central bore 69 and a downwardly extending fin 70. The 120 fin 70 is arranged to slide longitudinally of the casing within a guideway 71 formed between upstanding lugs 72, 73 secured to the bottom wall of the casing, and at 74 the yoke is provided with a stop lug arranged to 125 contact with the inner right-hand wall of the casing (see Fig. 2). The left-hand face of said yoke, as viewed in Fig. 2, is provided with a pair of bosses 75 (see also Fig. 4) against which the enlarged heads of the 130

two pistons bear, the springs 67, before described, serving to hold the respective heads 65 in engagement with said bosses, in the normal operation of the device.

5 76 is a drive-shaft passing through the bore 69 in the yoke and having its left-hand extremity, as seen in Fig. 2, seated within an opening in a boss 77 projecting from the right-hand face of the rib 20, the axis of 10 such shaft lying in a vertical plane substantially midway between the legs 39, 40. Carried by the shaft 76 at a point midway of its length is a helical cam 78 providing a gradual incline 79 which ends 15 in an abrupt shoulder 80. This cam is located within a longitudinal chamber 81 in the yoke member, and the latter is provided at a point within said chamber with a projecting lug or pin 82 arranged for engagement 20 by the cam 78.

The right-hand wall of the casing 10 has formed therein a large opening 83 within which is seated a casing 84 having a flange 85 bearing upon the outer face of the casing 10, said casing 84 having four outstanding ears 86 adapted to engage the bosses 25, upon the right-hand outer surface of the casing 10, and to be attached thereto by means of bolts 87 or other suitable securing means. The casing 84 also has an inturned flange 84^a at its end adjacent casing 10, said flange being cut away at one point as 84^b for a purpose to be described. The other end of the casing 84 is 30 provided with a reduced portion 88 providing a bearing opening 89 within which may turn a shaft 90, said shaft working in a stuffing box comprising a cap 91 having screw-thread engagement with the portion 40 88 of the casing. For holding the cap 91 in adjusted position, a nut lock may be provided, that herein shown consisting of a plate 91^a slotted at 91^b to take over one of the bolts 87 by means of which it may be 45 fixed in position. The face end of plate 91^a is notched out at 91^c to engage an angle of the cap 91 whereby the latter is held in desired position. The inner end of the shaft 90 has secured thereto or integral therewith, 50 a flange or collar 92 having a series of recesses 93 in its periphery (see Fig. 7), such recesses providing substantially flat surfaces 94, 95 arranged at an angle to each other and adapted for engagement by balls or rollers 96. At one end the recesses are provided 55 with pockets 97 within which are seated coil springs 98 against the ends of which the respective balls or rollers bear.

Surrounding the outer periphery of the 60 flange 92 is a retainer cup 99 having a substantially cylindrical inner surface engaging with the balls or rollers. The cup 99 is provided with a hub 100 having a central bore within which is seated the right-hand 65 end of the shaft 76 (see Fig. 9), the shaft

being held against rotation relatively to said hub by means of a key or other suitable device 101, it being understood, however, that the shaft may be freely withdrawn longitudinally from said hub.

70 Fixed to the hub 100 is a collar 102 which may be secured to the said hub by means of rivets 103 or other suitable securing means, said collar being provided with a series of recesses 104 similar in all respects to the 75 recesses 93 in the collar 92, such recesses being adapted to receive balls or rollers 105 which engage the inner surface of the casting 84; it being noted, however, that the arrangement of the recesses 104 is the reverse of that of the recesses 93.

Referring more particularly to Fig. 7, it will be noted that the wall 94 of the recess 93 approaches the interior wall of the retainer 99, and that the spring 98 tends to 80 force the ball or roller 96 toward the narrow end of the recess. Upon rotation of the flange 92 in the direction of the arrow α in Fig. 7, the ball or roller 96 tends to wedge 85 between the surface 94 and the interior surface of the retainer 99 whereby the latter is caused to rotate with the shaft 90. But upon reversal of the movement of shaft 90 the ball 96 moves away from the narrow end of the recess, thus releasing the retainer 99. 90 In inserting the rollers 96 in the casing 84, it is simply necessary to bring the recesses 93 successively opposite the opening 84^a, whereupon the rollers may be slipped into 95 place, and upon relative rotation of the parts 99 and 84 the flange 84^a is brought into retaining relation to the rollers, whereby the latter are held in operative position. By reason of this arrangement it is possible to remove the entire casing 84 with its 100 enclosed parts with little danger of losing any of them, the flange holding the rollers in position and thereby preventing displacement of the other parts.

Referring now to Fig. 1, it will be seen 110 that the connection 8 from the cross-head has pivotal connection with the crank arm 106, such crank arm being secured in any desired manner to the outwardly extending portion of the shaft 90. A convenient 115 means for securing such crank arm to the shaft may consist in forming the crank arm with a split end, as indicated at 107, 108, Fig. 2, and providing the shaft 90 with a tangential slot with which may engage the 120 side of a bolt 109 passing through the parts 107, 108, and by means of which said parts may be clamped securely about the shaft 90.

The oil from the lubricating device is fed 125 into the steam-feed pipe by means of a tube 110 inserted through the wall of said pipe and extending to a point substantially central thereof, said tube being inclined somewhat in the direction of steam flow to assist in the delivery of oil to the steam current. 130

As it is desirable that the drops of lubricant in passing into the steam be as minute as possible, it is convenient to provide a terminal check-valve adjacent the delivery end 5 of the pipe, such valve being illustrated in Fig. 11, in which the valve member is indicated as a ball 111 adapted to seat against a surface 112 formed in a chamber in a casting 113, such valve serving normally to close 10 the passage 114 leading from the delivery pipe of the pump element.

Under normal conditions the steam pressure would serve to maintain such a ball valve in closed position against its seat, 15 except when slightly opened intermittently by the pressure of lubricating fluid beneath the same, but in certain cases, as where the locomotive is drifting, a partial vacuum is formed in the steam inlet pipe which might 20 tend to hold open the valve and interfere with the proper lubricant delivery. In order to keep the valve properly seated under all conditions, it is provided with a stem 115 surrounding which is a coil spring 116 25 which may be placed under proper initial tension by means of a nut 117 engaging a screw-thread upon the stem 115. The terminal valve structure comprises a plurality of parts including casing 113 which may be 30 separated for proper adjustment of the valve, and with a clean-out opening 118 provided with a plug 119 through which the 35 valve may be examined and freed from accumulated grit or dirt, if necessary.

In the normal operation of the device, it being understood that it is mounted on the locomotive frame in the manner indicated, the receptacle 10 will be filled to desired level with oil, by pouring the latter through 40 the opening in the cover plate 29. The provision of the very large strainer 37 permits the rapid filling of the casing, and the pivoted cap 36 insures the exclusion of dirt and cinders from the interior of the receptacle, 45 while the location of the steam chamber 21 adjacent to and extending longitudinally between the legs 39 and 40 insures the proper heating of the lubricant throughout its travel through the pump passageways 50 without the necessity for raising the large body of fluid within casing 10 to an undesirably high degree.

The space at the bottom of the casing 10 below the guides 62 forms a sludge chamber and the provision of the annular chamber within strainer 39 insures a free flow of oil to the inlet passage 58 even if sludge is permitted to accumulate in the bottom of the casing to a level above said inlet.

Upon operation of the locomotive, movement is imparted to the connection 8 at every reciprocation of the cross-head, and thus, in direct correspondence to the speed 60 of the locomotive, the pump pistons are actuated, whereby oil is drawn through the

passage 58 through the bottom of the receptacle and forced upwardly through the check-valves 47, 48 and into the chamber 41, from which it flows through the passage in plug 42 and the connecting pipe 45 to the 70 terminal check valve. When the pressure becomes sufficient, the terminal check valve will be opened, and oil will be injected, drop by drop, into the steam inlet pipe.

As the connection 8 is reciprocated, the 75 crank arm 106 is rocked, and thereby through the ball ratchet, comprising the parts 92, 96 and 99, the shaft 76 is rocked, in a direction to cause the cam 78 to move the yoke 68 to the left, as seen in Fig. 2. 80 Such movement of the yoke, acting through the heads of the piston rods, serves to move the pistons to the left, thus forcing oil from the cylinders and into the chamber 41, as 85 above described.

Upon the reverse oscillation of the crank arm 106, the driving roller ratchet is idle, but the ratchet comprising the parts 102, 105 and 83 becomes active to prevent any 90 reverse movement of the shaft 76.

When the pin 82 reaches the position indicated by the left hand dotted circle (Fig. 10) at the end of the cam incline 79, it drops from abrupt shoulder 80 to the position indicated by the right hand dotted circle, and 95 the springs 67 immediately return the piston-rods with the pistons, together with the yoke 68, to initial position ready for a repetition of the operation. Such reverse movement through the action of the springs actuates the pistons on their suction stroke.

When, for any reason, it is desired to remove the pump element for cleaning or repairs, it is merely necessary to take out screws 31 and 38, whereupon the cover 29 105 may first be removed, and then the pump element, comprising the plate 26, the legs 39, 40, the bosses 52, with the pump cylinders, the guides 62, 63, the pistons and piston rods, and the actuating spring 67, may 110 all be lifted as a unit from the interior of the casing, and without necessitating the draining of oil therefrom. Furthermore if it is desired to remove the roller-ratchet mechanism for inspection or repairs, it is 115 only necessary to remove the bolts 87, whereupon the casing 83, together with all the inclosed parts, may be removed. The drive shaft 76 may then be removed from the casing, together with the yoke 68.

It will thus be seen that the entire operative mechanism of the lubricator may readily be removed with very little expenditure of time or labor. It will further be observed that all the operative parts of the 125 mechanism are fully inclosed and below the level of the oil in the casing 10, the parts thus being very thoroughly lubricated at all times. By reason of the arrangement of the pump cylinders at a point near the bot- 130

tom of the casing 10, it is unnecessary to provide the pump with an intake valve as the lubricant always flows freely into the cylinder in which a vacuum is formed upon 5 each back stroke of the pump sufficient to insure this action.

While as herein disclosed, the ratchet device for operating the drive shaft has been shown as of a roller clutch variety, it 10 is contemplated that ratchet device of other and well-known forms may be substituted therefor without affecting in any substantial manner the operation of the lubricating device.

15 It is furthermore to be understood that whereas but one pipe 45 has been shown leading from the lubricator, a similar pipe will, in the usual operation of the device, be arranged to lead to the other cylinder 20 of the locomotive, although it is within the scope of the invention to provide independent lubricating devices for the opposite sides of the locomotive. It is furthermore contemplated that under some circumstances, 25 as for example in locomotives of the compound type, it may be desirable to provide a comparatively large number of such delivery pipes leading from the lubricator; and in such cases it may become necessary 30 to provide a greater number of pump cylinders than that shown herein.

It is also contemplated that in some cases it may be found desirable to provide for 35 automatically lubricating certain of the mechanical parts of the locomotive, or of other machinery; and in such cases, oil from a lubricator pump of the type herein disclosed may be led to the points of use by means of suitably arranged conduits.

40 For adjusting the rate of flow of oil it is contemplated that levers 196 of various lengths will be provided, the length of the lever determining the throw of the ratchet device, under constant travel of lever 8. 45 Such a mode of adjustment is fool-proof and can be calculated for any given set of conditions with great nicety.

Having thus described the invention, together with the preferred embodiment of 50 the same and the mode of use thereof, what I claim and desire to secure by Letters Patent of the United States is:

1. In combination in a lubricating device, a pump element comprising a pair of substantially parallel pump cylinders, pistons arranged to reciprocate in said cylinders, a shaft interposed between said pistons, and means carried by said shaft for simultaneously moving said pistons in the same direction.

2. In combination in a device of the class described, a pump element comprising a pair of pump cylinders, pistons reciprocable within the said cylinders, a shaft rotatably supported between said pistons, a cam upon

said shaft and a cam follower actuatable by said cam and having connection to said pistons for simultaneous imparting the pressure stroke to said piston.

3. In a device for lubricating machinery, 70 in combination a pump comprising a piston, a rotatable shaft, a helical cam upon said shaft, said cam having a gradual rise and an abrupt descent, and a spring pressed cam follower engageable with said cam, and having 75 operative connection with said piston.

4. In a lubricating device, a pump comprising a plurality of parallel pistons, guides for said pistons, a yoke member constructed and arranged to contact with the ends of the 80 respective pistons, means for moving said yoke member whereby to impart the pressure stroke to said pistons, and spring means for holding said pistons in contact with said yoke member.

5. In a lubricating device of the class described, a casing, a pump element mounted in the casing, a pump cylinder therein and having its axis substantially parallel to the bottom wall of the casing, a piston movable 90 within said cylinder, and a shaft, having its axis substantially parallel to the axis of the piston, rotatably mounted in the casing, and means carried by said shaft for actuating the piston.

6. A lubricating device for steam engines, comprising, in combination, a casing for the reception of lubricating oil, a pump element 100 removably secured within said casing, said element being provided with a pump cylinder and with inlet and discharge passages therefor, said inlet being unprovided with a valve, a check valve in the discharge passage, a piston within the cylinder, an intermittently rotatable shaft within the casing, and 105 cam means upon said shaft for imparting the pressure stroke to the piston.

7. In a pump device, a support, a boss projecting therefrom, said boss having a bore therein constituting a pump cylinder 110 and having an intake passage leading thereto, a screen of foraminous material surrounding said boss and means for spacing said screen from said boss.

8. In combination in a lubricating device, 115 a casing, a pump cylinder located therein and having its axis substantially parallel to the bottom of the casing, a shaft within the casing and arranged substantially parallel to the axis of the pump cylinder, a piston 120 within the cylinder, a cam upon said shaft, a cam follower upon said piston, said cam being constructed and arranged to move the piston in one direction only, and a spring for moving the piston in the opposite direction.

9. In combination in a lubricating device, a pump element having therein a pair of parallel relatively stationary pump cylinders, pistons in the respective cylinders, a 130

yoke member connecting said pistons, said yoke member being provided with a guide, a guideway for said guide, a cam follower carried by said yoke member, a rotatable cam for moving said follower in one direction, and a spring for moving said follower in the opposite direction.

10. In a device of the class described, in combination, a casing having therein a pump element comprising pistons, a shaft rotatable within the casing and having its axis substantially parallel to the axes of said pistons, connections between said shaft and the pistons for actuating the latter, means for intermittently rotating the shaft, and means for locking the shaft against backward rotation.

11. In a device of the class described, in combination, a support, a substantially cylindrical boss extending from said support and having a fluid intake passage opening through its lateral wall, radial flanges extending from said boss at each end thereof, and a cylindrical screen surrounding said boss and having its ends seated upon the respective flanges.

12. In a device of the class described a pump element comprising a supporting member, a pair of spaced tubular legs depending therefrom, and lateral and substantially parallel bosses extending from the respective legs adjacent their free extremities, said bosses having parallel bores therein.

13. In a device of the class described a pump element comprising a pair of rigidly connected, substantially parallel legs, said legs having longitudinal passageways therein, bosses projecting from the respective legs and having substantially parallel bores therein, and guide members extending from said bosses and having guiding surfaces substantially parallel to the axes of said bores.

14. A device of the class described, comprising in combination a tubular support, a boss outstanding laterally from said support and provided with a substantially cylindrical bore forming a pump cylinder and a pair of spaced guide members extending outwardly from said boss and provided with guiding surfaces arranged substantially parallel with said bore.

15. A pump element for lubricating devices comprising in combination a tubular member having a supporting flange adjacent its upper end, a foot extending downwardly from its lower end, and a boss projecting laterally from said member and provided with a substantially cylindrical bore constituting a pump cylinder.

16. In a lubricating device, a pump comprising a plurality of cylinders, pistons in said cylinders, guides for the respective pistons, a piston actuating yoke engageable with the outer ends of the several pistons, mechanical means for moving said yoke, and

therethrough the pistons, in one direction, and springs engaging each of said pistons for moving them in the opposite direction.

17. In a lubricating device, in combination, a pump comprising a plurality of substantially parallel pistons, a yoke member engageable with the outer ends of said pistons, a guide for said yoke member, a cam for moving said yoke, and springs surrounding each of said pistons for moving them in a direction opposite to that imparted by the yoke.

18. In a lubricator, a pump element comprising a member having a pump cylinder formed therein, a piston in said cylinder, a pair of substantially parallel guides extending from said member and having slots therein, and a key member projecting from said piston and engaging within said slots.

19. In a device of the class described, in combination, a pump element comprising a pump cylinder, a piston therein, a drive shaft for actuating said piston, means for intermittently actuating said shaft comprising a roller ratchet, and a second roller ratchet for engaging said shaft and constructed and arranged to prevent rearward rotation thereof.

20. In combination in a lubricating device, a casing, a pump mechanism having a portion lying closely adjacent a side wall and its cylinder lying closely adjacent the bottom wall of said casing, a cover for said casing having an opening of relatively large diameter giving access to the space above and to one side of the pump mechanism, and a strainer of large diameter extending downwardly into said space from the opening.

21. In a lubricating device, a casing, a pump element therein comprising a member providing a horizontally arranged cylinder with inlet and discharge ports therefor, a piston, guides for the piston, and spring means for moving said piston in one direction and actuating mechanism located within said casing for moving the piston in the opposite direction, said pump element being constructed and arranged whereby it may be removed from the casing as a unit without disturbing the actuating mechanism.

22. In a lubricating device a casing forming a cistern for oil, a pump device within said casing comprising a piston and cylinder, said piston and cylinder being horizontally arranged and lying below the normal level of oil in said cistern and means for supporting said piston and cylinder within the casing constructed and arranged to permit removal of said piston and cylinder from the casing as a unit without draining the oil therefrom.

23. In combination in a lubricating device of the class described, a pump element comprising a pump cylinder and a discharge passage therefrom, check valves located

within said discharge passage, a discharge pipe leading from said passage, and a terminal check valve within said discharge pipe, said valve comprising a ball, a stem ⁵ therefor, and a spring for actuating said stem.

24. In a lubricator of the class described, a pump device having a fluid passageway therein, and a heating element located adjacent ¹⁰ said pump device and arranged substantially parallel to said passageway.

25. In a lubricator, a pump element provided with a pair of spaced apart legs having longitudinal fluid passageways therein, and a member arranged between said legs ¹⁵ and substantially parallel thereto and provided with a chamber for the reception of a heating medium.

Signed by me at Boston, Massachusetts, this fifth day of June 1920.

PHILIP G. DARLING.
